UNITED STATES PATENT OFFICE.

HOLISTER E. HESSLER, OF SYRACUSE, NEW YORK.

WASHING-MACHINE.

1,282,083.

Specification of Letters Patent. Patented Oct. 22, 1918.

Application filed May 4, 1910. Serial No. 559,311.

To all whom it may concern:

Be it known that I, HOLISTER E. HESSLER, of Syracuse, in the county of Onondaga and State of New York, have invented a certain 5 new and useful Washing-Machine, of which the following is a specification.

My invention has for its object a washing machine particularly applicable for washing baby cloths; and it consists in the combinations and constructions hereinafter set 10 forth and claimed.

In describing this invention, reference is had to the accompanying drawing in which like characters designate corresponding parts 15 in all the views.

Figure 1 is a longitudinal sectional view of this washing machine.

Fig. 2 is an inverted view of the bottom thereof.

20 Fig. 3 is an inverted view of the plunger or pounder.

1 is the receptacle of my washing machine for containing the cloths to be washed and the cleansing fluid, the receptacle having a 25 removable cover 2 formed with an opening 3 eccentrically placed thereon. The bottom of the receptacle is formed with an outlet opening 4 located near the side of the receptacle, and with a depending elliptical 30 flange 5 spaced apart from the edges of the receptacle and designed to fit within the bowl of an ordinary closet. The outlet opening 4 is located within the flange 5 and the portions or surfaces 6 of the bottom out- 35 side the flange are designed to rest upon the upper edge of such bowl.

7 is a perforated diaphragm located within the receptacle and spaced apart from the bottom thereof, the diaphragm resting at 40 its edges upon lugs 8 projecting from the side wall of the receptacle and said diaphragm having legs 9 which engage the bottom.

10 is a casing located within the receptacle in line with the opening 4, the casing being secured to the side wall of the receptacle and extending from near the top of the receptacle and terminating short of the bottom and extending through the diaphragm 45

50 7 which is provided with a cutout at its edge for the casing. 11 is a plug for the outlet opening 4, the plug having a stem 12 extending upwardly through the casing 10.

The casing 10 protects the stem from movement and accidental displacement by the 55

cloths within the receptacle above the diaphragm 7 during the washing of the cloths.

13 is a plunger or pounder movable within the receptacle 1 above the diaphragm 7 and comprising a conical head having a tubular stem 14 extending from its apex upwardly through the opening 3 of the cover 2. The head 13 is provided with a central annular wall or ring 15 depending from the conical wall of the head, and radially extending arms 16 extending from the lower edge of the annular wall or ring 15 to the lower edge of the conical wall of the head. The tubular stem 14 is stiffened by wires 17 arranged diametrically opposite each other 65 within the stem and extending the entire length thereof, these wires diverging outwardly at their upper ends and supporting a handle 18.

My washing machine is particularly advantageous in washing baby cloths, and in use, the receptacle is placed upon the bowl of a closet, the outlet opening being closed by the plug 11, and the cloths and washing fluid are placed within the receptacle, the 80 cloths resting on the diaphragm 7. The plunger or pounder 13 is then worked upwardly and downwardly and the cloths thoroughly kneaded therewith and when the cloths are washed the plug 11 is withdrawn 85 from the outlet hole 4 by means of the stem 12 permitting the fluid to drain through said hole and into the bowl of the closet. The cloths may then be rinsed with clean water which is pressed therefrom by forcing 90 the plunger downwardly and squeezing the cloths between the plunger and the diaphragm.

What I claim is:—

1. In a washing machine, a receptacle for holding the washing fluid and the material to be washed, movable means within the receptacle for coacting with the material to be washed, the receptacle having its bottom formed on the lower side thereof with a substantially elliptical depending flange set in from the edge of the bottom and designed to conform to the inner face of the upper end of the bowl of a closet, the receptacle also having a valve controlled outlet located 100 within such flange, substantially as and for the purpose described.

2. In a washing machine, a receptacle formed with an outlet opening in its bottom near one side thereof, and with an elliptical 110

flange depending from the bottom and spaced apart from the edges thereof, the outlet opening being located within the flange, the flange being designed to fit within the bowl 5 of a closet, and the portions of the bottom outside of the flange being designed to engage the upper edge of said bowl, a cover for the receptacle, the cover having an opening, a perforated diaphragm located within 10 the receptacle and spaced apart from the bottom, a casing contiguous to the side of the receptacle and alined with the outlet opening, the casing extending from near the upper edge of the receptacle and terminating 15 short of the bottom and extending through the diaphragm, a plug for the outlet opening having operating means extending upwardly

through the casing, and a pounder located within the receptacle above the diaphragm and having a stem extending upwardly 20 through the opening in the cover and being provided with a handle at its upper end, substantially as and for the purpose set forth.

In testimony whereof, I have hereunto 25 signed my name in the presence of two attesting witnesses, at Syracuse, in the county of Onondaga, in the State of New York, this 3rd day of February, 1910.

HOLISTER E. HESSLER.
